UNITED STATES PATENT OFFICE

168,820

HANGER BRACKET

Alexa L. Beltramini, New York, N. Y.

Application October 8, 1952, Serial No. 21,763

Term of patent 14 years

(Cl. D33—8)

To all whom it may concern:

Be it known that I, Alexa L. Beltramini, a citizen of the United States of America, residing in New York city, county of New York, and State of New York, have invented a new, original, and ornamental Design for a Hanger Bracket, of which the following is a specification, reference being had to the accompanying drawing, forming part thereof, wherein:

Figure 1 is a front perspective view of a hanger bracket, showing my new design.

Figure 2 is a rear elevational view of same in separated position.

Figure 3 is a side elevational view thereof, in separated position, drawn to a smaller scale.

I claim:

The ornamental design for a hanger bracket, substantially as shown.

ALEXA L. BELTRAMINI.
